UNITED STATES PATENT OFFICE.

HENRY B. COATS, OF Veedersburg, Indiana.

SPRING-WHEEL.

1,040,512.

Specification of Letters Patent.

Patented Oct. 8, 1912.

Application filed November 4, 1911. Serial No. 658,567.

To all whom it may concern:

Be it known that I, HENRY B. COATS, a citizen of the United States, residing at Veedersburg, in the county of Fountain and State 5 of Indiana, have invented a new and useful Spring-Wheel, of which the following is a specification.

The present invention aims to provide a resilient wheel which, at the option of the 10 user, may be fashioned without pneumatic elements of any sort.

A further object of the invention is to provide a resilient wheel in which, when pneumatic elements are used, these elements 15 will be securely housed within an inclosing structure, a puncture of the pneumatic elements being thereby avoided.

A further object of the invention is to provide a novel means for resiliently connecting an axle-carried supporting member 20 with an inclosing structure carrying the spokes and the felly of the wheel.

A further object of the invention is to provide novel means for preventing undue 25 friction between the supporting member and the casing wherein the supporting member is inclosed.

With the foregoing and other objects in view, which will appear as the description 30 proceeds, the invention resides in the combination and arrangement of parts and in the details of construction hereinafter described and claimed, it being understood that changes in the precise embodiment of invention here- 35 in disclosed can be made within the scope of what is claimed without departing from the spirit of the invention.

In the accompanying drawings,--Figure 1 shows the invention in fragmental side elevation; Fig. 2 is a section upon the line A—B of Fig. 1; Fig. 3 is a section upon the line C—D of Fig. 2; Fig. 4 is a fragmental radial section, showing the means whereby the anti-friction elements are carried by the 45 supporting member, for engagement with opposite sides of the casing in which the supporting member is inclosed; and Fig. 5 is a fragmental sectional elevation showing a modified means whereby the supporting member may be resiliently connected with the inclosing casing.

In carrying out the invention there is provided an inclosing casing, including a spoke plate 1, from which the spokes 2 radiate, the 50 spokes 2 carrying a rim 3, supporting the tire 4, which may be of any desired form.

Secured to, and preferably formed integrally with the spoke plate 1, and constituting a part of the casing 1, is an inner, side plate 5. The opposite side of the casing is 60 closed by a removable side plate 6, held in place upon the spoke plate 1 by securing elements 8, of any desired form, the outer side plate 6 being equipped with a projecting, axle-receiving cap 7.

The invention further includes a brake drum 9, located adjacent, but upon the outside of, the inner side plate 5, the brake drum 9 having a tubular extension 10, adapted to receive and to be secured to, the axle 70 11, the axle 11 and the tubular extension 10 constituting what, for convenience, will be referred to hereinafter as the axle structure. This axle structure protrudes through openings 12 in the side plates 5 and 6, the 75 openings 12 being of considerably greater diameters than the diameter of the extension 10, the construction being such that the casing, embracing the side plates 5 and 6, may have movement transversely of the axle 80 structure.

Fixed to the tubular extension 10, is a supporting member 14, preferably taking the form of a plate, this supporting member having a series of spaced openings 15. 85 Shafts 16 extend through the openings 15, the extremities of the shafts 16 being secured to the side plates 5 and 6, the diameter of the openings 15 being much greater than the diameters of the shafts 16. The shafts 90 16 carry, within the peripheries of the openings 15, wheels 17, the peripheries of which are inclosed by inflatable, pneumatic tires 18, these tires 18 being adapted to bear against the peripheries of the openings 15 95 in the supporting member 14.

Means is provided for spacing the supporting member 14 anti-frictionally from the side plates 5 and 6 of the casing. This means includes a series of ball cages, inserted transversely through the supporting member 14. The ball cages, as will be discerned readily from an inspection of Fig. 4, comprise separable parts 19, threaded into the supporting member 14, the parts 105 19 being equipped with nuts 20, adapted to bear against the opposite faces of the supporting member 14, to maintain the parts of the ball cages in the supporting member. Rotatably mounted within the ball cages, 110 are anti-friction balls 21, the ends of the parts 19 of the ball cages being contracted,

as shown at 22, to maintain the balls 21 in anti-frictional contact with each other, adjacent the median plane of the wheel. The balls 21 protrude beyond the contracted ends

5 22 of the ball cages, and engage with the side plates 5 and 6, as will be understood readily from an inspection of Fig. 4.

If desired, the invention may be modified to the extent indicated in Fig. 5. Referring 10 to Fig. 5, the casing is shown as comprising a spoke plate 23, from which the spokes 24 radiate. The supporting member is denoted by the numeral 25, the same having the openings 26, hereinbefore referred to. 15 Through these openings 26 project the shafts 27, the shafts 27 being connected with the side plates of the casing as hereinbefore described. Located within the openings 26 are a plurality of radially positioned, helical 20 springs 28. Of these springs 28 there may be any number. The inner ends of the springs 28 are secured to the shafts 27, the outer ends of the springs being connected with eyes 29 or the like, projecting inwardly 25 into the openings 26, and secured to the supporting member 25.

Referring particularly to that form of the invention which is shown in Figs. 1 and 2, it 30 will be understood that when rotation is imparted to the axle 11 and to the tubular end 10 of the brake drum 9, this rotatory motion will be communicated to the supporting member 14 which is rigidly united with the tubular end 10 of the brake drum 9. When 35 the supporting member 14 is rotated in the manner hereinbefore described, rotatory motion will be communicated to the casing, comprising the members 1, 5 and 6, through the pneumatic tires 18, through the wheels 40 17, and through the shafts 16 which are terminally connected with the side plates 5 and 6. Thus, as will be understood readily, the wheel will be rotated, the construction being such that there will be no creeping of the 45 casing circumferentially of the supporting member 14. Owing to the fact that the inflatable pneumatic tires 18 are interposed between the peripheries of the wheels 17 and the peripheries of the openings 15 in the 50 supporting member 14, the casing 1-5-6 will have movement transversely of the axle structure 10-11, the openings 12 in the side plates 5 and 6 permitting this movement. However, owing to the fact that the balls 21 55 engage with each other adjacent the median plane of the wheel, and owing to the further fact that these balls engage anti-frictionally with the side plates 5 and 6, upon both sides of the supporting member 14, the 60 wheel, considered as an entity, will have no appreciable lateral movement with respect to the axle 11.

In that form of the invention which is shown in Fig. 5, the only change involved, 65 is the substitution of the springs 28 for the

wheels 17 and the tires 18. The wheel shown in Fig. 5, will operate in the same manner as the wheel shown in Figs. 1 and following.

In pneumatic wheels, as commonly constructed, wherein the periphery of the wheel is inclosed by a pneumatic tire, the wheel is put entirely out of commission when this tire is deflated, accidentally or otherwise. In the device disclosed in Figs. 1 and 2, 70 should one of the tires 18 be deflated, the resiliency of the wheel will be impaired to a small extent only, it being entirely feasible to continue the journey with one or more of the tires 18 in bursted or deflated condition. 80 The same remarks apply with respect to the springs 28. One or more of these groups of springs 28 may become broken or "killed", without interfering seriously with the resiliency of the wheel, and certainly, without 85 rendering the wheel totally inoperative.

In pneumatic wheels as commonly constructed, there is a continuous strain upon the tire wherewith the periphery of the wheel is surrounded. In the present invention, the tires 18, upon the one hand, or the groups of springs 28, upon the other hand, are alternately submitted to a maximum strain, which strain is relieved at regular intervals. The resilient elements, in the device constituting the subject matter of this application are, therefore, under maximum strain at spaced intervals, the life of the resilient elements being thereby greatly prolonged.

Having thus described the invention, what is claimed is:—

1. In a device of the class described, an axle structure; a supporting member secured to the axle structure and provided with openings; a casing inclosing the supporting member and adapted to have movement transversely of the axle; shafts terminally connected with the casing and extended through the openings; resilient means interposed between the shafts and the periphery of the openings; separable ball cages extended through the supporting member; means for retaining the ball cages in the supporting member; and balls held in the ball cages, the balls being adapted to bear against the casing upon both sides of the supporting member, and to bear against each other adjacent the median plane of the device.

2. In a device of the class described, an axle structure; a supporting member secured to the axle structure and provided with openings; a casing inclosing the supporting member and adapted to have movement transversely of the axle; shafts terminally connected with the casing and extended through the openings; wheels upon the shafts; pneumatic tires carried by the peripheries of the wheels and adapted to bear against the peripheries of the openings; sep-

arable ball cages extended through the supporting member; means for maintaining the ball cages in the supporting member; and balls held in the ball cages, the balls being adapted to bear against the casing upon both sides of the supporting member, and to bear against each other adjacent the median plane of the device.

In testimony that I claim the foregoing as my own, I have hereto affixed my signature 10 in the presence of two witnesses.

HENRY B. COATS.
